UNITED STATES PATENT OFFICE.

HERBERT T. HERR, OF PITTSBURGH, PENNSYLVANIA, ASSIGNOR TO WESTINGHOUSE ELECTRIC & MANUFACTURING CO., A CORPORATION OF PENNSYLVANIA.

GEARED-POWER-DEVELOPING UNIT.

1,384,834.

Specification of Letters Patent. Patented July 19, 1921.

Application filed September 8, 1917. Serial No. 190,389.

To all whom it may concern:

Be it known that I, HERBERT T. HERR, a citizen of the United States, and a resident of Pittsburgh, in the county of Allegheny and State of Pennsylvania, have made a new and useful Invention in Geared-Power-Developing Units, of which the following is a specification.

This invention relates to turbine apparatus and has for an object to produce an improved geared power developing unit which is of simpler and more rigid construction and is more compact than similar units now in use and known to me.

15 A further object is to produce a self-contained unit including a compound turbine and a reduction gearing in which both sections of the compound turbine are adapted to deliver power to the driving pinion of the reduction gearing.

20 These and other objects, which will be made apparent throughout the further description of my invention, are attained by means of apparatus embodying the features herein described and illustrated in the drawings accompanying and forming a part hereof.

25 In the drawings: Figure 1 is a sectional plan view of a geared unit embodying my invention.

30 Fig. 2 is a fragmental perspective view, on an enlarged scale, of blading forming a detail of the apparatus illustrated in Fig. 1.

In the drawings I have illustrated an embodiment of my invention, which includes a cross compound turbine in which the rotor elements of both turbine sections are directly connected to the same pinion of the reduction gearing. As illustrated, the turbine includes a high pressure or initial section 3 and a low pressure section 4, which receives the partially expanded steam exhaust from the initial section. The sections 3 and 4 and the reduction gearing 5 are so arranged that the combined apparatus is, in effect, a self-contained geared turbine unit which may be secured to a ship's structure or other foundation by a single seating.

35 The reduction gearing includes a driving gear or pinion 6 and a driven gear 7, which meshes with the pinion 6. As illustrated, the gear and pinion are of the usual construction, each being provided with two sets of oppositely inclined gear teeth and each 40 being journaled in bearings formed or

mounted in a casing 8. Both ends of the mounting shaft of the pinion 6 are overhung and the rotor element 3^a of the initial section 3 is mounted on one end of the shaft, whereas the rotor element 4^a of the low pressure section 4 is mounted on the other end of the shaft. A housing 3^b incloses the rotor 3^a of the turbine section 3 and is mounted on the gearing casing 8. A housing 4^b forms a part of the section 4 and is also mounted on the gearing casing 8.

45 The initial section 3 may be of any suitable type but is preferably of the reentry type including a single row of moving blades. As shown, the rotor 3^a is equipped with radially extending blades 9, which are shrouded and which receive steam from one or more steam nozzles 10. The nozzles 10 communicate with a steam chest 11 which receives steam through an inlet port 12 provided in the housing 3^b. The nozzles 10 are preferably divergent nozzles and capable of expanding the steam traversing them to the pressure at which it is discharged from the initial section. The steam issuing from the nozzles 10 traverses the blades 9 and is received by a redirecting passage 13, which directs and redelivers it to the blades 9 in the usual manner. The number of redirecting passages employed will depend somewhat on the conditions encountered but, generally speaking, any number may be employed. The steam finally discharged from the blades 9 passes through an exhaust port 14, with which the casing 3^b is provided, and is delivered by means of a pipe or passage 15 to the inlet port of the low pressure section 4. The inlet port of the section 4 communicates with an annular steam chest 16 which delivers steam to a series of nozzles 17. The nozzles 17 are preferably adapted to expand the steam received by them to exhaust or condenser pressure, and the nozzles are preferably arranged in an annular series extending around the entire periphery of the wheel 4^a. As illustrated, the nozzles 17 deliver the steam so expanded by them to a single row of blades 18 mounted on the rotor wheel 4^a.

50 In marine installation, it is necessary to reverse the direction of rotation to the driven parts and for that reason it is customary to provide a reversing turbine or turbine section as a part of the propelling apparatus. In the drawings I have illustrated a revers- 105

ing section as a part of the low pressure section 4. In Fig. 2, I have shown the form of ahead and reversing blades which may be employed in the low pressure section. The blades 18 of the ahead section are provided with a shroud which is made up in separate sections, each section being integrally formed with one of the blades 18. These sections engage each other and form the shroud and are so formed 5 that they provide a row of peripheral buckets 19 which form the working elements of the reversing section. Steam or motive fluid is delivered to these elements by means of one or more nozzles 20 which communicate with 10 the steam chest 20^a formed in the casing 4^b and receiving steam through the inlet 4^c. Steam issuing from the reversing section and also from the ahead blades of the low pressure section 4 is discharged through an 15 exhaust port 21 which, as illustrated, is of substantially the same cross sectional area as the casing 4^b. Either or both sections may be provided with a reversing section, and the two reversing sections may be com- 20 pounded as desired.

A packing 25 is provided between the housing 3^b and the shaft on which the pinion 6 and rotor 3^a are mounted. A similar packing is provided between the casing 30 4^b and the other end of the shaft, and an open pocket 26 is formed between each housing and the casing 8, to permit easy removal of oil and water leakage from the bearings and packings respectively. The housing 3^b is shown divided at 26^a on a plane passing 35 through the axis of the pinion shaft. The casing 8 and housing 4^b are similarly divided, and consequently a portion of the combined casing may be removed for the pur- 40 pose of removing the pinion with the rotor elements attached. This may be accomplished without removing the entire housings from the casing and without removing all of the steam connections from the tur- 45 bine sections.

While I have described and illustrated but one embodiment of my invention, it will be apparent to those skilled in the art that various modifications, changes, additions 50 and omissions may be made in the apparatus illustrated without departing from the spirit and scope of the invention, as set forth by the appended claims.

What I claim is:

1. In combination in a geared turbine 55 unit, a driving gear, a driven gear meshing therewith, an inclosing casing for said gears in which said gears are mounted, a turbine housing mounted on each side of said casing, and a turbine rotor inclosed in each housing, each rotor being mounted on the shaft of the driving gear. 60

2. In combination in a geared turbine unit, a driving gear, a driven gear, a casing in which said gears are mounted, a turbine 65 rotor mounted on each overhanging end of the shaft of the driving gear, and a separate housing for each rotor mounted on said casing.

3. In combination in a geared turbine 70 unit, a driving gear, a driven gear meshing therewith, a casing in which said gears are journaled, in combination with two turbine sections, each comprising a rotor element mounted on the shaft of the driving gear, 75 and a housing mounted on the casing, and ahead and reversing blades mounted on one of said elements.

4. In combination, a high pressure turbine section, a low pressure turbine section axially 80 alined therewith, reduction gearing inter- posed between said sections for transmitting the power developed by both of said sections and axially alined therewith, a shaft com- 85 mon to the gearing and both turbine sec- tions, and casing elements bolted together to form a unit for inclosing said gearing, said shaft and both turbine sections.

5. A marine turbine apparatus comprising a driving gear, a driven gear meshing 90 therewith, a turbine rotor element mounted on an overhanging end of the shaft of the driving gear, a second rotor element mounted on the opposite overhanging end of said shaft, ahead and reversing blading mounted 95 on one of said sections, and a casing for each of said rotor elements and said gearing whereby said apparatus may be secured to the ship's structure by a single seating.

In testimony whereof, I have hereunto 100 subscribed my name this 6th day of September, 1917.

HERBERT T. HERR.

Witness:

C. W. McGHEE.
